BASE FOR OUTDOOR LAMP POLES OR THE LIKE

Henry C. Pfaff, Jr., Summit, and Francis G. Schlosser,
Carteret, N.J., assignors to Pfaff and Kendall, Newark,
N.J., a corporation of New Jersey

Filed July 17, 1962, Ser. No. 71,038

Term of patent 14 years

(Cl. D48—31)

FIG. 1

Des. 198,099

PAGE 2

FIG.2

FIG.4

FIG. 3

FIG. 1 is a top plan view of a base for outdoor lamp poles or the like, embodying our design,

FIGURE 2 is a perspective view of the base shown in FIGURE 1.

FIG. 3 is a top plan view of a modified form of the base shown in FIG. 1.

FIGURE 4 is a perspective view of the base shown in FIGURE 3.

This application is a continuation-in-part of our pending applications D. 68,218 filed January 8, 1962, and D. 68,239 filed January 9, 1962, both now abandoned.

We claim:

The ornamental design for a base for outdoor lamp poles or the like, as shown and described.
